Patented July 1, 1919.

FIG. 1

FIG. 3

FIG. 2-14

FIG. 4

Inventor
George H. Bell,
by Herbert W. Jenner.
Attorney

UNITED STATES PATENT OFFICE.

GEORGE HENRY BELL, OF BROOKLYN, NEW YORK; HARRIET L. BELL EXECUTRIX OF
SAID GEORGE HENRY BELL, DECEASED.

VAPORIZER.

1,308,571.

Specification of Letters Patent.

Patented July 1, 1919.

Application filed February 26, 1918. Serial No. 219,248.

To all whom it may concern:

Be it known that I, GEORGE H. BELL, a citizen of the United States, residing in the borough of Brooklyn, city of New York, and State of New York, have invented certain new and useful Improvements in Vaporizers, of which the following is a specification.

This invention relates to vaporizers for generating steam and medicated vapor for medical use; and it consists in the novel construction and combination of the parts hereinafter fully described and claimed.

In the drawings, Figure 1 is a front view of a vaporizer constructed according to this invention. Fig. 2 is a sectional plan view of the frame, taken on the line *x—x* in Fig. 1. Fig. 3 is a vertical section through the vaporizer taken through the frame on the line *y—y* in Fig. 2. Fig. 4 is a sectional detail view, taken on the line *z—z* in Fig. 2.

An annular base 2 of sheet metal is provided, and it has a central hole 3 for the lamp, and a series of curved slots 4 arranged circumferentially around the hole 3. The frame 5 is tubular, and is formed of thin sheet metal bent to cylindrical form, and provided with an opening 6 at its front side for the insertion and removal of the lamp. The frame is also provided with inlet holes 7 for air at its lower part, and outlet holes 8 for the products of combustion above them. The vertical meeting edges of the sheet metal are preferably connected by a lap joint or hook joint 9, and vertical slots 10 are formed in the plate one on each side of the joint. A clip plate 12 is provided, and is inserted through the slots 10 from the inside of the frame, and its projecting portions are bent around to form eyes 14. These eyes secure the clip plate in place, and loop-shaped handles 15 are pivoted in them, and are used in handling the vaporizer. The clip plate secures the frame at its joint, and any approved form of joint may be used.

The bottom of the frame is provided with projecting tongues 16 which are inserted through the slots 4 of the base, and are bent around under the base so that the frame and

its base are rigidly secured together. By following this construction the use of solder joints is avoided, solder joints being liable to melt in a device of this sort.

The upper part of the frame is provided with a circumferential bead 17 to stiffen it, and the metal at the top edge is bent double to form a stiffening ring 18.

The lamp 20 is any approved form of spirit lamp, and its alcohol holder has a circumferential rib 21 which rests on the bottom or base when the holder is inserted in the hole 3. The holder is made to fit the hole 3 snugly, so that the lamp cannot accidentally be displaced when the vaporizer is moved about and tilted. The wick tube 22 is connected to the alcohol holder in any suitable way, and a diaphragm plate 24 is secured to it so as to form a considerable space 25 between the plate 24 and the holder. This diaphragm plate prevents the downward passage of flame and heat to the alcohol holder, and the cool air which enters through the inlet holes 7 circulates under the diaphragm plate and keeps the alcohol holder and the lower part of the wick tube cool.

The boiler 28 is formed of sheet metal, and it has a projection 29 around its upper edge which rests on the top of the frame. A neck 30 is formed at the top of the boiler, and 31 is a perforated cup which is supported in the neck 30. This cup is removable, and cotton wool is placed in it, and is saturated with any suitable medicament, such as benzoin in solution.

A cap 32 is secured over the neck, and is provided with a conical projecting nozzle 33 for the escape of steam or medicated vapor generated in the boiler by the heat of the lamp beneath it.

The boiler or the cap can be turned around to point the nozzle in any desired direction, and the vaporizer can be placed on a table to inhale the steam, or it can be moved about by hand to apply a jet of steam to any desired portion of the body.

What I claim is:

In a vaporizer, a tubular frame of sheet metal having its edges permanently secured

together by a longitudinal joint, said frame having two relatively long longitudinal slots formed in it and arranged one on each side of the said joint, a clip plate having its 5 middle part arranged to bear on the said joint on the inside of the frame and having its side portions inserted through the two slots and bent around to form eyes and to bear on the outside of the frame thereby

strengthening the joint, handles engaging 10 with the said eyes, a boiler provided with an outlet nozzle and supported by the said frame, and means for heating the boiler arranged underneath it inside the frame.

In testimony whereof I have affixed my 15 signature.

GEORGE HENRY BELL.
